UNITED STATES PATENT OFFICE

152,990

DESIGN FOR AN ADJUSTABLE ANTENNA

Ralph N. Leonard, Crystal Lake, Ill.

Application October 8, 1948, Serial No. 149,035

Term of patent 7 years

(Cl. D26—14)

To all whom it may concern:

Be it known that I, Ralph N. Leonard, a citizen of the United States and a resident of Crystal Lake, county of McHenry, and State of Illinois, have invented a new, original, and ornamental Design for an Adjustable Antenna, of which the following is a specification, reference being had to the accompanying drawing, forming a part thereof, in which Fig. 1 is a perspective view of an adjustable antenna, showing my new design, with the antenna arms thereof adjusted in one position; Fig. 2 is a horizontal sectional view as

taken on the line 2—2 and on a scale enlarged over that of Fig. 1; and Fig. 3 is a view similar to Fig. 1 but with the antenna arms adjusted in a position different from that shown in Fig. 1.

The opposite side of the antenna is substantially like that shown in Figs. 1 and 3.

I claim:

The ornamental design for an adjustable antenna, substantially as shown and described.

RALPH N. LEONARD.
